METHOD AND MEANS FOR PRODUCING
ABRADING ROLLS FOR USE ON ABRAD-
ING OR POLISHING MACHINESEarl E. Price, Minneapolis, Minn., assignor to
G. H. Tennant Company, Minneapolis, Minn.,
a corporation of Minnesota

Application July 1, 1935, Serial No. 29,305

22 Claims. (Cl. 140—92.2)

This invention relates to improvements in machines for producing abrading rolls, composed of steel wool or functionally equivalent material, wound on a suitable base, and to a method of 5 winding such rolls to produce a roll which will not cause streaking of the surface upon which it is used.

One of the problems in the art of making abrasive rollers by the use of steel wool has heretofore been to so wind the abrasive material as to prevent what is known as "streaking" of a floor or other uneven surface being cleaned or abraded by the roll. I have found that this streaking is due to uneven winding, or to such close packing 15 of the material, during formation of the roll, that various parts thereof cannot yield conformably to inequalities in the surface being abraded or polished.

I have found that streaking is largely overcome if a softer more yieldable core layer is initially 20 formed or provided, and if a more unyieldable layer or cylinder of abrasive material is superposed upon this softer cushioning layer. In this way, an inner cushion is provided which allows the various areas of the more hardly packed material to move inwardly and accommodate themselves to the non-coplanar or upstanding inequalities in the surface being abraded or cleaned.

Although the winding material often used is what may be termed a "ribbon", and although this 30 ribbon is applied in formation of the product by spirally winding it back and forth on a suitable drum, the present machine is also capable of properly winding a broad sheet of material on the roll something in the manner of toweling on a towel roll, as distinguished from the winding of a narrow ribbon on the long roll and the overlapping spiral arrangement of the margins of this ribbon with the margin of the ribbon already wound. A 35 cushion core, as herein contemplated, in combination with a surrounding harder cylinder of material is useful for either form of winding.

Features of the invention include: all details of construction of the machine; combinations and 40 sub-combinations of the parts; the method of manipulating the elements of the machine during winding to obtain a product which, when in use, overcomes streaking; and to all broader ideas of means inherent in the disclosure.

Objects, features and advantages of the invention will be set forth in the description of the drawings forming a part of this application, and in said drawings:

Figure 1 is a side elevation with the treading 50 rolls retracted to inoperative position, and with

the treading roll frame latched in inoperative position, and showing in dot-and-dash lines the operative position of the treading rolls, frame and associated control parts;

Figure 2 is a plan view of the structure of Figure 1, partly in section;

Figure 3 is a transverse section, taken approximately on line 3—3 of Figure 2;

Figure 4 is a sectional-elevation taken approximately on line 4—4 of Figure 1;

Figure 5 is a vertical sectional-elevation taken on line 5—5 of Figure 2, illustrating the controlling means for the pressure-adjustable flattening and guide rolls;

Figure 6 is a vertical section taken on line 6—6 of Figure 2, illustrating the pressure-adjusting means for the flattening rolls;

Figure 7 is a fragmentary elevation of the flattening rolls viewed from the right-hand side of Figure 3;

Figure 8 is a plan section taken on line 8—8 of Figure 1, illustrating the pivotal relation of the lower ends of the side bars of the roller carrying frame, and part of the treadle bar; and

Figure 9 is a perspective view of the improved 25 spool shell.

In the drawings, numeral 1 generally designates a suitable supporting framework or frame. On top of the frame is mounted a hollow spindle 2 which is journaled in a manner to have its outer 30 end free. I have referred to this spindle as an "outboard" spindle. To obtain this outboard type of mounting, the spindle is provided interiorly with a bearing 3 which receives one end of a shaft 4, which shaft is suitably keyed to the bearing and 35 is journaled as at 5 in a boxing attached by bolts to the top of the frame. The shaft 4 is attached to one part of a coupling 6, to another part of which coupling is attached a shaft 7, in turn connected with suitable reducing gearing, not 40 shown, but contained in casing 8. The gearing is, in turn, connected with a shaft of a motor 9. The motor is controlled, see Figure 1, by a rheostat-operating construction generally indicated at 10 (not claimed herein) and this is controlled by 45 bar 11, connected with arm 12 of horizontal shaft 13. Shaft 13 has a treadle 14 and a spring 15 normally moves the rheostat to motor-off position.

The hollow spindle is open at its outer end, which end is reduced as at 20 and has threads 21 50 cooperating with threads 22 of a disk 23, which disk forms an auxiliary head cooperative with one of the heads 25 of a spool shell generally indicated at 26.

The head has a shaft 28, rotative in a journal 55

box 29, pivotally mounted on a swinging support or arm 30, pivoted on a vertical stub shaft 31 suitably held as by bracket 33 at the side of frame 1. The shaft 28 is provided with a hand 5 wheel 35 and the threads 21, 22 cooperate to move the disk to operative position against the flange 25 of the spool shell 26 when the disk is temporarily held against rotation by means of the wheel 35, while the spindle is rotated in 10 winding direction. When winding is completed, the wheel is operated to unscrew the head, and the head is swung outwardly to the dotted line position shown in Figure 2, to allow removal of the completed abrading roll.

15 Oscillation of the journal box 29 of shaft 28 is limited by a screw 29^a threaded in upright portion 29^b of the frame 30.

Referring to Figure 9: The shell 26, in addition to the head-forming flanges 25, has on its 20 outer surface means cooperable with the initially presented end of the material being wound to entrain the same in winding direction. In this instance, this means consists of a plurality of portions 40 each formed by punching out the 25 metal, and each providing rough fingers. The shell is also provided with a plurality of circumscribing outwardly projecting elements 41. The elements 40 project a greater distance outwardly beyond the surface of the shell than the 30 elements 41. The elements 41 together with the head flanges 25 prevent axial movement of the wound material.

A feature of this invention is the means for 35 releasably but non-rotatably connecting the shell to the spindle, and a feature is the use of the diametrically opposed slots 46 extending axially inwardly from one end of the spindle for a distance equal to about one-half the length of the spindle. This feature is related to the use 40 of the machine for winding shells of different axial length, and to the non-rotative connection of these shells by a cross bar traversing the slots. The cross bar 42 is arranged diametrically and is secured by means including annular enlargements 45 on the bar arranged at the inner side of the shell. Each enlargement 43 is of a diameter only slightly less than the width of the slot. The slots are elongated to receive the bars of shells of different sizes.

50 The inner end of the spindle is also provided with screw threads 47, which extend a substantial distance lengthwise. A head 48 has threads cooperating with the threads 47, whereby this head may be adjusted lengthwise of the spindle 55 to be pressed against the flange 25 of a shorter shell. A suitable set screw 49 secures the disk in any adjusted position.

An important feature of the invention relates 60 to means for applying pressure against the material being wound to properly and evenly pack it, as winding proceeds. To this end there is provided a frame including side elements 50 pivoted, see Figures 1 and 8, at their lower ends to a cross-shaft 51 of the frame 1. Lateral motions 65 of the frame elements 50 are prevented by means of guides 50^a supported on horizontal irons 50^b of the frame 1. This frame is arranged rearwardly of the spindle and extends upwardly and is adapted to swing toward and away from the spindle. The frame is yieldably urged toward the spindle, in this instance by gravity-operable means including, see Figures 1 and 4, a rod 60 having a weight 61 slidably adjustable thereon. The rod is secured by means of a suitable bracket 75 et 63 to a shaft 62 journaled in the frame 1.

Secured to this shaft is an arm 64 connected by a link 65 to a bracket or iron 66 suitably secured to the side elements 50. The weight acting through the elements just described urges the frame toward the spindle.

Means is also provided for retracting the frame and latching it in retracted position. This control means is operable from a point in front of the machine, by an operator who is manipulating the material for winding. To this end, the shaft 62 has an arm 67 connected by a link 68 to a foot treadle bar 69, pivoted on shaft 51, see Figure 1. This bar extends forwardly and is provided with a foot-engaging portion 70. In Figure 1, the frame is shown in full lines as retracted, and the bar 69 is releasably latchingly engaged with an element 71. Unlatching is accomplished by pressing downwardly on 70, and then moving the bar 69 laterally, and finally allowing weight 61 to retract the frame and move 20 the bar 69 upwardly to the dot-and-dash line positions shown.

An important feature is the method of packing by means of a plurality of rollers; a single row, or a plurality of rows. What is believed to 25 be the first means by which the method can be carried out is herebelow described.

Mounted on the frame formed in part by the bars 50 are a plurality of rows of spaced rollers, each of which is independently spring-pressed 30 toward the shell. Means is provided by which the spring tension can be adjusted. Referring to Figure 3, each of these rollers 79 is mounted on an arm 80 which is swingingly mounted on a shaft 81 held by and connecting the arms 50. 35 The arms are spaced by suitable collars 81^a, see Figure 2, and axial motion of the assembly is prevented by collars and pins 81^b. Each rod 81 is releasably secured by collars and pins 81^c. There are upper and lower rows of these rollers 40 79. Each arm is independently spring-pressed toward the shell by means of spring 82 arranged over a threaded rod 83. One end of the rod is pivotally connected as at 84 to a bracket of the arm, and the rod slidably traverses an opening 45 in an angle iron 85, and has a nut 86 adjustable for limiting sliding movement of the arm, and therefore for limiting the degree of swing of the arm 80. The tension of the spring is adjusted by means of a nut 87. It is noted that by removal 50 of the shafts 81 and removal of the nuts 86, some of the arms and rollers thereon may be removed. Thus the number of rollers can be varied conformably to the axial length of the shell. The use of rollers avoids dulling of the strands and 55 the consequent reduction in cutting or abrading efficiency of the roll. The edges of the rolls are slightly rounded and the rolls have a "tucking in" action on the material.

The axes of the rollers are substantially parallel with the rotative axis of the spindle, and the rows are spaced circumferentially but are adjacently disposed, see Figure 4. The rows of one roll are so related to those of another that their circumferential areas of contact overlap. A single row can be used, or more than two rows may be employed. Two rows arranged as shown are preferred.

The rollers are arranged to apply pressure at 70 a point about ninety degrees or more forwardly of the point at which the oncoming material engages the material on the spool. The arrangement of the rollers at about ninety degrees forwardly of that point appears to be most advantageous.

By use of the weight 61 pressing the frame forwardly, and by use of a spring for each roll, constant "treading" pressures are applied to every part of the material being wound, and for the 5 full length of the material in an axial direction. The rolls, in any event, are so arranged as to maintain a plurality of separately applied pressures throughout. This feature in combination with the provision of a soft core layer on the shell 10 with an over-wound harder cylinder of abrasive material, provides an article which, for its intended use, is much superior in its abrading action to any other known to me.

As previously mentioned, a feature of this invention relates to a method for producing a steel wool abrading roll which, when in use, will not cause what is known as streaking of a floor or other uneven surface being cleaned or abraded. The method consists in initially forming on the 20 spool shell a cushioning core, by initially winding a sufficient amount of wool on the spool shell preferably without pressure, and then applying to the material separate yielding pressures by the means of this invention, as 25 winding continues, to produce a relatively more closely packed cylinder of material about the cushioning core or softer layers. This produces an article which is much superior in its abrading action than any other known to me.

30 Another feature of the invention relates to the use of pressure guide rolls, see Figures 5, 6 and 7; also Figures 2 and 3. The lower roll 90 is suitably journaled on stub shaft 91, which shaft is held in two arms of a bracket 92, secured to the 35 top of frame 1. The upper roll 93 is journaled on shaft 94 held in plate 95, see Figures 2 and 6, pivoted as at 96 to bracket 92.

These rolls are herein called yieldable pressure guide rolls, and are arranged in front of the 40 spool for flattening the wool before winding. It is desirable to maintain an even thickness of the material and to vary the thickness. To control and vary the thickness, means is provided for adjusting the swinging plate 95 for the upper roll. 45 This means is best shown in Figure 6 and comprises a vertical stem 98 rotative in swinging bracket 95 and in horizontal portion 99 of bracket 92. Stem 98 has a hand wheel 101 at its top and is held against translative movement in one direction by collar 102 held by pin 103. On the lower end of a stem is a threaded tension-adjusting nut 105 and surrounding the shaft and under compression between the nut and the portion 99 of the bracket 92 is a spring 106. The upper roll 50 is pressed lightly against the lower roll to obtain proper flattening and winding drag on the material, and this drag is further varied by a bar herebelow described.

In order to raise the roll 94 against the action 55 of the spring 106, a cam is provided, see Figure 5. The cam is indicated at 110 and is secured on a collar 111 swingable on shaft 91, the collar being held against axial movement by collar 112 suitably pinned to the shaft. An operating 60 handle 114 is provided for the cam, and the cam has an upwardly directed portion 115 acting as a stop engaging the shaft 94 to limit the forward movement. When the handle is moved in direction of the arrow, the roll 93 is raised 65 against the action of spring 106 so that the material can be introduced between the rolls 93.

Another feature of the invention is the arrangement of the bar 117 in front of the rolls to provide means against which the wool can be 70 dragged before entering the rolls. The purpose

of the dragging is to stretch the material in direction of its motion, thereby getting rid of most of the inequalities and decreasing the thickness. The wool is indicated at 118. Although not shown, it will be understood that the supply 5 of wool is arranged on another roll held on a shaft, which shaft is suitably held in a support.

The material before being brought against the bar 117 and between the rolls 90 and 93 is passed through a piece of pipe (not shown) which pipe 10 is held in the operator's hand to enable him to move the material in a direction axially of the bar and rolls to obtain, in case a ribbon of material is used, an overlapping spiral winding of 15 the material on the shell.

In the operation, the roll or steel wool which is to be transferred to the spool shell is suitably mounted and a portion of the material is pulled forwardly and passed between the rolls which are at this time separated. The forward end is then laid on the shell and rotation of the shell is started by hand. The elements on the outer surface of the shell cooperate with the initially presented end of the material to entrain the same in winding direction. The proper number 20 of turns is made to provide the soft cushioning core, and then the roll 93 is lowered to operative position. The rollers are now brought to operative position, and power is applied and winding is continued, to surround the soft core by 25 a harder cylinder of material. Due to varying thickness of the material being wound, it is necessary to pull the material against the drag bar. 30

I claim as my invention:

1. A machine for winding steel wool or other suitable material comprising a driven spindle, said spindle having non-rotatably and removably secured thereon a spool shell, disks on said spindle forming auxiliary heads for said spool, means removably securing one of said disks, plural rows of spaced rollers each independently yieldably spring-pressed toward the shell, means by which all rollers can be simultaneously moved to operative or non-operative position relatively to material being wound, the axes of the rollers being substantially parallel with the rotative axis of the spindle, said rows being spaced circumferentially but being adjacently disposed, the rollers of one row being offset relatively to the rollers of another row so that the areas of contact of the rollers of one row overlap those of another, whereby a plurality of treading pressures are applied to the material. 35

2. A machine for winding steel wool or other suitable material comprising, a driven spindle, 40 said spindle having non-rotatably and removably secured thereon a spool shell, disks on said spindle forming auxiliary heads for the spool, means removably securing one of said disks, plural rows of spaced rollers independently 45 spring-pressed toward the shell, means by which the rollers can be adjusted toward and away from and pressed against material being wound on the shell, the axes of the rollers being substantially parallel with the rotative axis of the spindle, said rows of rollers being spaced circumferentially but being adjacently disposed and the rollers of one row being so related to those of another that their circumferential areas of contact overlap. 50

3. A machine for winding steel wool or other suitable material comprising, a driven spindle, so rotatably mounted as to permit the introduction thereonto or removal therefrom of a spool shell, said spindle having non-rotatably and re- 55

movably secured thereon a spool shell, disks on said spindle forming auxiliary heads for the spool, means removably securing one of said disks, a frame adapted to swing toward and away 5 from the shell, a row of spaced rollers, means for each roller attaching it to the frame and yieldably urging it toward the shell, the axes of the rollers being substantially parallel with the rotative axis of the spindle, and yieldable means 10 acting on the frame to forcibly move it to cause the rollers to maintain a yielding pressure contact with the material being wound.

4. A machine for winding steel wool or other suitable material, comprising a driven spindle 15 having a first spool-head disk at its inner end, means journaling the spindle at said inner end only, thus leaving the outer end free, a second spool-head disk, said disk and free end of the spindle having screw threads cooperating to operably 20 secure the disk to the spindle, said spindle having non-rotatably secured thereon a removable spool shell for which the disks form auxiliary heads, a frame adapted to swing toward and away from the spindle, plural rows of spaced rollers, 25 means for each roller detachably securing it to the frame, and yieldably urging it toward the shell, the axes of the rollers being parallel with the rotative axis of the spindle, and yieldable means acting on the frame to forcibly move it to 30 cause the rollers to maintain a yielding pressure contact with the material being wound.

5. A machine for winding steel wool or other suitable material comprising, a driven spindle having a first spool-head disk at the inner end, 35 means journaling the spindle at said inner end only, thus leaving the outer end free, a swingable support having a journal box pivoted thereto, a second spool-head disk journaled in said box, the free end of said spindle having screw 40 threads operably securing the disk to the spindle, said spindle having non-rotatably and removably secured thereon a spool shell for which said disks form heads, a frame adapted to swing toward and away from the spindle, plural rows 45 of spaced rollers, separate means for each roller attaching it to the frame and yieldably urging it toward the shell, the axes of the rolls of each row being aligned and the axes of one row being parallel with the axes of the other and with the 50 rotative axis of the spindle, said rows of rolls being adjacently disposed and the rollers of one row being so related to the rollers of another that their circumferential areas of contact with the material being wound overlap, and yieldable 55 means acting on the frame to forcibly move it to cause the rolls to maintain a yielding pressure contact with the material on the shell.

6. A machine for winding steel wool or other suitable material comprising, a driven spindle 60 having a first spool-head disk at its inner end, means journaling the spindle at said inner end only, thus leaving the outer end free, a swingable support having a journal box pivoted thereto, a second spool-head disk having a shaft journaled in said box, a hand wheel for said shaft, 65 said disk and free end of the spindle having screw threads cooperating to operably secure the disk to the spindle, said threads being adapted, when the disk is temporarily held against rotation, to cause said disk to be moved to operative position as a result of rotation of the spindle in winding direction, said spindle having removably and non-rotatably secured thereon a spool shell for which the disks form heads, a 70 frame adapted to swing toward and away from

the spindle, plural rows of spaced swingingly mounted arms on the frame, each arm having a roller, the axes of the rollers being substantially parallel with the rotative axis of the spindle, said rows of rollers being adjacently disposed but spaced circumferentially yieldable means for each arm forcing it toward the shell, and yieldable means acting on the frame to cause the rollers to maintain a yielding pressure contact with the material being wound. 10

7. A machine for winding steel wool or other suitable material comprising a driven spindle having a first spool-head disk at the inner end, means journaling the spindle at said inner end only, thus leaving the outer end free, a second spool-head disk having screw threads cooperating to operably secure the disk to the spindle, said spindle having non-rotatably secured thereon a removable spool shell for which said disks act as heads, a frame at the rear side of the spindle adapted to swing toward and away therefrom, plural rows of spaced swingingly mounted arms on the frame, each arm having a roller, the axes of the rollers of each row being aligned and the axis of one row being parallel with the other and with the rotative axis of the spindle, said rows of rolls being adjacently disposed, yieldable means for each arm forcing it toward the spindle, yieldable means acting on the frame to forcibly move it to cause the rollers to maintain a yielding pressure contact with the material being wound, and means by which the frame can be retracted and latched in retracted position, said means adapted to be controllable by an operator while controlling the feeding material to the spool. 20

8. A machine for winding steel wool or other suitable material, comprising, a driven spindle having spool-head disks, a winding spool shell held non-rotatably on the spindle between the 40 disks, a frame adapted to swing forwardly and away from the spindle, plural rows of swingingly mounted arms on the frame, each arm having a roll, the axes of the rolls of each row being aligned, and being parallel with the rotative axis 45 of the spindle, said rows of rolls being adjacently disposed and being adapted to engage the material being wound at a point ninety degrees or more forwardly of the point at which the oncoming material engages the material on the 50 spool, yieldable means for each arm forcing it toward the spindle, and yieldable means acting on the frame to forcibly move it to cause the rolls to maintain a yielding pressure contact with the material on the spool. 55

9. A machine for winding steel wool or other suitable material, comprising a driven spindle having a first spool head disk fixed at the inner end, means journaling the spindle at the inner end only thus leaving the outer end free, 60 a second spool head disk for the free end of the spindle and means detachably securing said disk to said spindle, a shell spool held non-rotatably on the spindle for which the disks form heads, a frame adapted to swing forwardly and away from the spindle, plural rows of swingingly mounted arms on the frame, each arm having a roll, the axes of the rolls of each row being aligned and being parallel with the rotative axis 65 of the spindle, said rows of rolls being adjacently disposed and being adapted to engage the material being wound at a point about ninety degrees or more forwardly of the point at which the oncoming material engages the material on the spool, yieldable means for each arm forc- 70 75

ing it toward the spindle, and yieldable means acting on the frame to forcibly move it to cause the rolls to maintain a yielding pressure contact with the material on the spool.

5 10. A device for winding steel wool or other suitable material comprising, a driven spindle, a spool shell slidably fitting the spindle and means for preventing rotation of the shell on the spindle, said spindle having disks secured thereto for cooperation with the ends of the spool shell heads to form auxiliary heads which are of substantially greater diameter than said spool shell heads, one of the disks being detachably secured, and said shell having its outer surface provided 15 with means cooperable with the initially presented end of the material being wound to entrain the same in winding direction.

11. A device for winding steel wool or other suitable material comprising, a driven spindle, a spool shell slidably fitting the spindle and means for preventing rotation of the shell on the spindle, said spindle having disks secured thereto and forming auxiliary heads for the spool shell which auxiliary heads are of substantially greater diameter than said spool shell heads, one of the disks being detachably secured, and said shell having its outer surface provided with means cooperable with the initially presented end of the material being wound to entrain the same in winding direction, and said shell having a plurality of circumferential outwardly projecting elements spaced lengthwise of the shell, the said entraining means projecting a greater distance outwardly beyond the surface of the shell than 35 said circumferential projecting elements.

12. A device for winding steel wool or other suitable material comprising, a driven spindle, said spindle having a pair of diametrically opposed slots extending axially inward from one end for a distance equal to about one-half the length of the spindle, a spool shell slidably fitting the spindle and having secured thereto a cross bar which bar is disposed in said slots to prevent rotation of the shell on the spindle, said spindle 45 having disks secured thereto and forming auxiliary heads for the spool shell which heads are of substantially greater diameter than said spool shell heads, one of the disks being detachably secured.

50 13. A device for winding steel wool or other suitable material comprising, a driven spindle, a spool shell slidably fitting the spindle, disks secured to the spindle and forming auxiliary heads for the heads of the spool shell, said shell having its outer surface provided with means cooperable with the initially presented end of the material being wound to entrain the same in winding direction.

14. A device for winding steel wool or other suitable material comprising a driven spindle, said spindle having a pair of diametrically opposed slots extending axially inward from one end, a spool shell slidably fitting the spindle, and having means detachably engaged with the slots 65 to non-rotatably secure the spool to the spindle, said shell having its outer surface provided with means cooperable with the initially presented end of the material being wound to entrain the same in winding direction and said shell having a plurality of circumferential outwardly projecting elements spaced lengthwise of the shell, the said entraining means projecting a greater distance outwardly beyond the surface of the shell than 70 said circumferential projecting elements.

75 15. A machine for winding steel wool or other

suitable material comprising, a driven spindle, a spool shell detachably secured to said spindle and upon which the material is to be wound, a pair of pressure guide rolls arranged in front of the spindle for flattening the wool before winding, means by which one of the rolls is yieldably pressed toward the other, and a friction bar arranged in front of the rolls against which the wool can be dragged before entering the rolls.

16. A machine for winding steel wool or the like comprising a driven spindle adapted to have a spool shell non-rotatably secured thereto, a pair of yieldable pressure guide rolls arranged in front of the spool for flattening the wool before winding on the shell, a bar arranged in front of the rolls against which the wool can be dragged before entering the rolls, plural rows of spaced rollers and a separate means for each roller for yieldably urging it toward the spindle, a support upon which the rollers are mounted, said support being movable to simultaneously withdraw or advance all rollers, the rollers of one row being so related to another that their areas of contact overlap.

17. A method for winding steel wool on a spool shell to produce an abrading element for use on abrading machines which consists in initially winding the wool on the shell to produce a cushioning core, and then applying such pressure to the material as winding continues to produce a relatively more closely packed cylinder of material about said cushioning core, and applying such pressure without destroying the cushioning condition of the core.

18. A method for winding steel wool on a spool shell to produce an abrading element for use on abrading machines which consists in initially winding the wool on the shell, to produce a cushioning core, and then applying yielding pressure to the material as winding continues to produce a relatively more closely packed cylinder of material about the cushioning core, and applying such pressure without destroying the cushioning condition of the core.

19. A method for winding steel wool on a spool shell to produce an abrading element for use on abrading machines which consists in initially winding a plurality of layers of the wool on the spool shell to produce a cushioning core, and then applying pressure to the material as winding continues, by using a plurality of independently yieldable pressure rollers so arranged that their areas of contact overlap, and completing the winding to produce a relatively more closely packed cylinder of material about the soft core, and applying such pressure without destroying the cushioning condition of the core.

20. A method for winding steel wool on a spool shell to produce an abrading element for use on abrading machines which consists, in initially winding a plurality of layers of the wool on the shell to produce a cushioning core and then applying pressure to the material as winding continues, using a plurality of rows of independently yieldable pressure rollers so arranged that their areas of contact overlap to evenly and continuously apply pressure to provide a relatively more closely packed cylinder of material about the soft core, and applying such pressure without destroying the cushioning condition of the core.

21. A device for producing a steel wool abrading element attachable to the spindle of an abrading machine, comprising a driven spindle, a thin sheet metal one-piece spool shell having

shallow heads, means by which the shell is detachably held on the spindle, disks secured to the spindle and forming deep auxiliary heads for the heads of the spool shell, one of said disks being detachable to allow removal of the shell, the metal of said shell being punched outwardly to provide means cooperable with the initially presented end of the material being wound to entrain the same in winding direction.

10 22. A method for producing a steel wool abrading element which will not cause streaking of

a wooden surface on which it is used and which includes a shell attachable to the spindle of an abrading machine, which consists in initially winding the wool on the shell to produce a cushioning core, and then applying yieldable pressure to the material as winding continues to produce a relatively more closely packed cylinder of material about the cushioning core, and applying such pressure without destroying the cushioning condition of the core.
